UNITED STATES PATENT OFFICE

170,155

SPECTACLE FRAME ORNAMENT

Anthony Di Chiara, Newark, N. J., assignor to
Liberty Optical Company, Inc., Newark, N. J.

Application August 4, 1952, Serial No. 20,892

Term of patent 14 years

(Cl. D57—1)

To all whom it may concern:

Be it known that I, Anthony Di Chiara, a citizen of the United States of America, residing at Newark, in the county of Essex and State of New Jersey, have invented a new, original, and ornamental Design for a Spectacle Frame Ornament, of which the following is a specification, reference being had to the accompanying drawing, forming a part thereof.

In the drawing:

Figure 1 is a front elevational view of a spectacle frame ornament showing my new design,

Figure 2 is a rear elevational view thereof; and
Figure 3 is a side elevational view.

I claim:

The ornamental design for a spectacle frame ornament, as shown.

ANTHONY DI CHIARA.
